CLAIM

The ornamental design for a fluid emitter for a drip irrigation system, as shown and described.

DESCRIPTION

FIG. 1 is a front elevational view of the fluid emitter for a drip irrigation system showing my new design;
FIG. 2 is a rear elevational view thereof;
FIG. 3 is a left side elevational view thereof;
FIG. 4 is a right side elevational view thereof;
FIG. 5 is a top plan view thereof on an enlarged scale;
FIG. 6 is a bottom plan view thereof on an enlarged scale; and,
FIG. 7 is an isometric view thereof.

FIG. 1

FIG. 2

*FIG. 3**FIG. 4**FIG. 5*

FIG. 6

FIG. 7
